D. C. HUSTED

MAGNETO POST

Filed April 11, 1922

FIG. 1.

FIG. 2.

Inventor
Don C. Husted
by Robert W. Denner,
Attorney.

UNITED STATES PATENT OFFICE.

DON C. HUSTED, OF MARSHALL, OKLAHOMA.

MAGNETO POST.

Application filed April 11, 1922. Serial No. 551,616.

To all whom it may concern:

Be it known that I, DON C. HUSTED, a citizen of the United States, residing at Marshall, in the county of Logan and State 5 of Oklahoma, have invented certain new and useful Improvements in Magneto Posts, of which the following is a specification.

This invention relates to magneto posts for connecting electric wires with the coils 10 of the magnetos used on motor cars in connection with internal combustion engines; and it consists in the novel construction and combination of the parts hereinafter fully described and claimed, whereby a good elec- 15 tric contact is assured, and whereby the device can be removed and replaced with facility.

In the drawings, Figure 1 is a side view of a magneto post constructed according to 20 this invention, and showing the fastening disk in section. Fig. 2 is an end view of the device.

The post body 4 has an insulator 5 secured in it, and 6 is a rod electrode secured 25 in the insulator and provided at one end with a helical spring coil for making contact with the magneto. The outer end of the rod 6 has nuts 7 for the attachment of the electric wire 8 in the usual manner.

30 A portion 10 of the casing of the magneto is shown, and it has an opening 12 to admit the inner end portion of the insulator. A fastening disk 14 is provided, and is secured permanently by screws 15 to the casing 10 around the opening 12. This disk 14 has a tubular center portion 16 and a peripheral flange 18 which project from it in the same direction and form an annular groove. The center portion 16 is screwthreaded internally 35 to engage with and support the post body. A packing cylinder 17 is arranged between

the disk 14 and the side of the magneto casing, and its outer end is inserted in the said annular groove. This packing cylinder holds the center portion 16 and the flange 45 18 clear of the casing, and it has holes for the fastening screws 15. The hole 12 in the casing is smaller in diameter than the center portion 16, as it only requires to be large enough to admit the insulator 5. The flange 50 18 also stiffens the disk, and prevents it from being distorted.

The post body is screwthreaded externally, and is screwed into the tubular center portion 16, and it has a hexagonal 55 outer part 20 for a wrench to engage with. The post body can be removed and replaced with great facility, whenever the point of the spring needs cleaning, or some other purpose makes it desirable to remove the 60 post body.

What I claim is:

A magneto contact comprising a short tubular body adapted to be arranged about the magneto contact opening of a magneto 65 casing, an annular disk applied to the outer end of the short tubular body and having inner and outer strengthening flanges defining an annular groove snugly receiving the outer portion of said short tubular body, 70 said inner strengthening flange being internally threaded, a contact member threaded through said inner flange and extending beyond the inner end of said short tubular member, and fastening devices ex- 75 tending through said annular disk and said body and adapted to connect the body to a magneto casing.

In testimony whereof I have affixed my signature.

DON C. HUSTED.
